COMPENSATED AMPLIFIER

Otto H. Schmitt, Port Washington, N. Y., assignor to the United States of America as represented by the Secretary of the Navy

Application February 8, 1944, Serial No. 521,559

1 Claim. (Cl. 179—171)

1

This invention relates to an improved compensated amplifier, and more particularly to an amplifier especially adapted for use with a filament or a current supply having relatively wide voltage fluctuations.

Amplifiers of the type employing thermionic vacuum tubes ordinarily require a source of power to heat the filaments or heaters of the vacuum tubes. Fluctuations in the voltage of this power source cause the electron emission from the cathodes of the vacuum tubes to vary over wide limits. This variation in the electron emission, if the frequency pass band of the amplifier is such as to include the frequency of change in cathode emission due to filament-voltage fluctuations, will produce a spurious signal in the output of the amplifier.

In amplifiers for use in applications where relatively complete freedom from spurious responses is required, and where it is necessary to energize the filaments of the vacuum tubes from a source of current subject to wide voltage fluctuations, it is essential that some arrangement be provided substantially to compensate for the deleterious effects of these fluctuations. In the past, such compensation means have comprised relatively complicated and expensive networks which, while providing satisfactory compensation, in themselves introduced many potential sources of trouble.

It is an object of the present invention, therefore, to provide a compensation arrangement of improved and simplified design, which nevertheless is capable of substantially reducing the spurious responses which may result from fluctuations in the voltage of the filament-supply source. By the use of a single suitably chosen additional vacuum tube properly associated with the amplifier vacuum tube, for example, an improvement of the order of 30:1 may be secured with the arrangement of the present invention.

In accordance with the present invention, there is provided, in an amplifier including a vacuum tube having a control electrode and a thermionic cathode variable impedance, means for minimizing spurious responses in the output of the amplifier due to variations in the temperature of the cathode. This variable impedance means is utilized to develop a source of direct-current voltage which is made to vary substantially in proportion to the variations in the electron emission from the cathode, and connections for applying this direct-current voltage to the control electrode in such a manner that the mean plate current of the vacuum tube is held substantially constant in spite of the variations in the electron emission from its cathode.

While the improved compensation arrangement of the present invention is adaptable for use in any type of vacuum-tube amplifier, its use is

2

especially advantageous in amplifiers designed to amplify direct-current and extremely low-frequency voltages. In such amplifiers, spurious responses, whatever their cause, are usually considerably more serious than in the case of amplifiers for voltages of higher frequencies. Experiments have indicated that such spurious responses are in large part due to fluctuations in the emission of electrons from the cathode of the amplifying vacuum tube, such variations in emission being due in turn to fluctuations in voltage of the filament supply. By utilizing the arrangement of the present invention, therefore, a very marked improvement in the performance of the amplifier may be realized in those cases where the filaments are subjected to fluctuating voltage.

For a better understanding of the invention, together with other and further objects thereof, reference is made to the following description taken in connection with the accompanying drawing, and its scope will be pointed out in the appended claim.

In the accompanying drawing:

Fig. 1 is a circuit diagram, partly in block form, of a compensated amplifier arranged in accordance with the present invention; and

Fig. 2 shows, partly in block form, a modification of the amplifier of Fig. 1, also in accordance with the present invention.

Referring now to Fig. 1 of the drawing, there is shown an amplifier, having input terminals 1, 2, and output terminals 3 and 4, including amplifying vacuum tube 5. Resistor 6 is connected between input terminals 1 and 2. Input terminal 1 is connected to one terminal of potentiometer 7, the slider of which is connected through battery 8 to grid 9 of vacuum tube 5. Input terminal 2 is grounded, as is also cathode 10 of vacuum tube 5. Plate 11 of vacuum tube 5 is connected to output terminal 3 and also, through resistor 12, to a source of positive potential indicated at B+. Output terminal 4 is also connected to B+.

Cathode 13 of vacuum tube 14 is connected to input terminal 1. Grid 15 and plate 16 of vacuum tube 14 are connected together and to one terminal of potentiometer 7. Filaments or heaters 17 and 18, respectively of vacuum tubes 5 and 14, are connected to a source of power 19.

In operation, vacuum tube 5 operates in the usual manner as an amplifier, in a desired region of its characteristic curve as determined by the voltage of battery 8. A signal applied to input terminals 1 and 2, therefore, appears across output terminals 3 and 4 substantially unchanged in wave form but of appreciably greater magnitude.

Assuming for the moment that the voltage of source 19 remains constant at its normal value, the small residual current which flows through vacuum tube 14 operating as a diode produces a potential drop across potentiometer 7 having the

polarity indicated. A portion of this potential drop, depending upon the setting of the slider of potentiometer 7, is applied to grid 9 of vacuum tube 5 with such a polarity as to supplement the voltage of battery 8. In practice, the voltage of battery 8 is so chosen as to allow for this relatively small supplemental voltage, so that vacuum tube 5 operates in the desired region of its characteristic curve.

Now let it be assumed that the voltage of source 19 rises appreciably above its normal value. The higher voltage which is now applied to filament 17 of vacuum tube 5 causes the temperature of cathode 10 to increase, with the result that the electron emission from this cathode also increases. The effect of this is to cause a larger plate current to flow through resistor 12 than would flow were the cathode at its normal temperature. The potential drop appearing across resistor 12 would thus be greater than that normally corresponding with the input signal applied to terminals 1 and 2. Such an undesired spurious response, however, is greatly minimized by the action of vacuum tube 14. Any increase in the voltage of source 19 obviously increases the temperature of filament 18 and hence of cathode 13 of vacuum tube 14. This in turn causes a larger current to flow through vacuum tube 14, thereby producing a larger potential drop across potentiometer 7. When a portion of this increased voltage is applied to grid 9 of vacuum tube 5, the bias voltage on this grid is shifted in a negative direction, thereby changing the operating point of vacuum tube 5 and somewhat decreasing its mean plate current. The magnitude and direction of this shift in the operating point is such as substantially to compensate for the increase in electron emission from cathode 10 which was described above. The net result is that the potential drop across resistor 12 is substantially the same as that obtained under the normal condition of operation at the rated filament voltage.

Consider now the operation of the system when the voltage of source 19 is considerably less than normal. In this case, the temperature of filament 17 decreases, as does the temperature and hence the emission of cathode 10, both of vacuum tube 5. The obvious result would be a decrease in the current flowing through vacuum tube 5 and hence in the potential drop across resistor 12. The simultaneous decrease in the temperature of filament 18 of vacuum tube 14, however, causes a decrease in the current flowing through this tube and hence a decrease in the voltage developed across potentiometer 7. This in turn shifts the region of operation of vacuum tube 5 on its characteristic curve in such a sense as to increase its mean plate current. As a result, the signal voltage which is developed across resistor 12 is substantially the same as that which would be developed under conditions of normal operation at the rated filament voltage.

The modification of Fig. 2 of the drawing is substantially the same in arrangement as that of Fig. 1, and identical in operation. In Fig. 1, input terminal 2 is grounded, and cathode 13 of vacuum tube 14 operates at a potential above ground. In the arrangement of Fig. 2, on the other hand, cathodes 10 and 13 are both grounded, and both of input terminals 1 and 2 are above ground. This rearrangement thus consists merely in placing vacuum tube 14 and its associated circuit components in the low-potential side of the input circuit of vacuum tube 5, rather than in

the high-potential side of this circuit as in Fig. 1.

In both of Figs. 1 and 2, the purpose of potentiometer 7 is to regulate the effectiveness of the compensation for filament-voltage fluctuations. In practice, this potentiometer is initially adjusted for optimum performance, and this adjustment normally remains unchanged until one or both of vacuum tubes 5 and 14 is replaced.

In one successful embodiment of the invention, in accordance with either of Figs. 1 and 2, an improvement of approximately 30:1 in stability was realized compared with a similar amplifier without compensation.

In this embodiment vacuum tubes 5 and 14 each comprised one-half of a type 6SN7 tube; resistor 6 and potentiometer 7 each had a value of 1.0 megohm; resistor 12 had a value of 10,000 ohms; battery 8 had a voltage of 6.0 volts; and the source of positive potential B+ had a voltage of 180 volts. Source 19 was a battery having a nominal voltage of 6.3 volts, and the actual voltage ranged from 4 to 10 volts.

While there has been described what is at present considered the preferred embodiment of the invention, it will be obvious to those skilled in the art that various changes and modifications may be made therein without departing from the invention, and it is, therefore, aimed in the appended claim to cover all such changes and modifications as fall within the true spirit and scope of the invention.

What is claimed is:

In a direct current amplifier, the combination comprising input and output terminals, an impedance unit connected in shunt across said input terminals, a first thermionic vacuum tube having an anode, control electrode, indirectly heated cathode and a filamentary heater therefor, said heater being connected to a source of direct current, a variable impedance network comprising a second thermionic vacuum tube having an anode, indirectly heated cathode and a filamentary heater therefor, said heater being connected also to said source of direct current and responsive to the same variations of potential as the filamentary heater of said first tube, a potentiometer comprising an adjustable tapped resistor connected directly across the cathode and anode of said second tube, means applied to the adjustable tap of said resistor and the cathode of said second tube for connecting said variable impedance network in series with said first tube cathode, control electrode and impedance unit, a load impedance connected to the anode of said first tube and means connecting said load impedance across said output terminals, whereby variations in the source of direct current will not deleteriously affect the current through said load impedance.
